UNITED STATES PATENT OFFICE

125,631

DESIGN FOR A BADGE OR SIMILAR ARTICLE

Victor F. Casaretti, Brooklyn, N. Y.

Application July 29, 1940, Serial No. 93,989

Term of patent 7 years

To all whom it may concern:

Be it known that Victor F. Casaretti, a citizen of the United States of America, residing at Brooklyn, in the county of Kings and State of New York, has invented a new, original, and ornamental Design for a Badge or Similar Article, of which the following is a specification, reference being had to the accompanying drawing, forming part thereof.

I claim:

The ornamental design for a badge or similar article, as shown.

VICTOR F. CASARETTI,
